UNITED STATES PATENT OFFICE.

FREDRICK N. ARNOLD, OF BUFFALO, NEW YORK.

MIXING APPARATUS.

1,181,205.

Specification of Letters Patent.

Patented May 2, 1916.

Application filed July 9, 1914. Serial No. 849,902.

To all whom it may concern:

Be it known that I, FREDRICK N. ARNOLD, a citizen of the United States, residing at Buffalo, in the county of Erie and 5 State of New York, have invented a new and useful Improvement in Mixing Apparatus, of which the following is a specification.

This invention relates more particularly 10 to apparatus for use in hydrogenizing fats and oils, although the apparatus is not limited to such use but is also adapted for mixing liquids or other substances with a gas or vapor.

15 The objects of this invention are to provide an apparatus of this kind which will insure a rapid and thorough mixing of a liquid either with or without solid material contained therein, with a gas or vapor, as, 20 for example, in the reduction of fatty acids and glycerids or other reduceable materials with hydrogen or other reducing gas or vapor, or in the saponification of glycerids to fatty acids and glycerin.

25 In hydrogenizing fats and oils it has been found that the mere passing of the hydrogen through the fat or oil does not cause the gas to be readily absorbed, and that a more intimate mixing will greatly 30 reduce the time required to produce the desired reduction. The apparatus disclosed is particularly desirable for producing the required intimate mixture and greatly reduces the time required for hydrogenizing 35 fats and oils.

40 In the accompanying drawings: Figure 1 is a central sectional elevation of an apparatus embodying the invention. Fig. 2 is a sectional plan view thereof on line 2—2, Fig. 1.

A represents a closed tank or receptacle of suitable construction adapted to contain the materials to be mixed. The tank shown is cylindrical and is mounted in upright position 45 on suitable supports or legs *a* and is provided with a manhole *a'* and with admission or discharge pipes *a²* *a³* for the liquid and a pipe *a⁴* for the admission of the gas or vapor. The pipe *a⁴* is provided with 50 a valve *a⁵* leading to the atmosphere, and a valve *a⁶* controlling the admission of gas or vapor to the tank from a supply pipe *a⁷*. All of these parts may be of any suitable or usual construction.

55 The mixing of the liquid with the gas or vapor is accomplished in the apparatus

shown by imparting a rotary motion to the liquid in the lower portion of the tank and causing the whirling liquid to be thrown upwardly into the space above the body of 60 liquid which is occupied by the gas or vapor. by means of blades or deflectors which depend into the liquid. The liquid is preferably thrown violently against the top of 65 the tank so that it is broken up and descends through the gas space in a shower, spray or 70 mist, thus causing all portions of the liquid to come into intimate contact with the gas. In the construction shown for this purpose, a whirling motion is imparted to the liquid 75 by means of paddles or agitators *B* *B'* projecting laterally from a vertical rotary shaft *b*, which extends into the tank preferably through a suitable stuffing box *b'* on the top of the tank. This shaft is preferably suspended from a suitable support *b²* by means of a bearing *b³* so that no bearing for the shaft is required in the tank. The lower portion of the shaft is centered in the 80 tank and steadied by means of a suitable guide bracket *b⁴* secured to the bottom of the tank. Movement may be imparted to the shaft in any suitable manner, for example by means of bevel gears *b⁵* *b⁶* connecting the mixing shaft with a drive shaft *b⁷*. 85 The paddles may be of any suitable construction, those shown being substantially flat and inclined with regard to the direction of movement thereof. One paddle *B* is preferably located adjacent to the upper 90 surface of the liquid and the other paddle *B'* is arranged near the bottom of the tank where it serves to move the liquid from the bottom of the tank upwardly.

The whirling liquid which partially fills 95 the tank is deflected upwardly through the gas or vapor in the tank by means of a plurality of deflectors or blades *C*, secured in the tank, for example to the side walls thereof. The lower ends of the deflectors extend 100 into the liquid and are inclined from the vertical, so that the deflector will scoop up the liquid which will flow upwardly along the deflectors, and if the liquid in the tank is whirled with sufficient speed, the liquid 105 will be dashed against the top of the tank and will fall in a shower, spray or mist of finely broken up particles through the gas space, as indicated by the dotted lines in Fig. 1. In order to prevent the centrifugal force 110 of the liquid from causing the liquid which moves upwardly on the deflectors to hug the

walls of the tank, each deflector is inclined at its upper portion in the direction of movement of the liquid in the tank, at an angle to a radial line of the tank so that the deflectors tend to cause the liquid to flow toward the center of the tank.

It is frequently necessary to heat the liquid to be acted upon, for which purpose coils D, for steam or other heating medium, 10 are provided inside of the tank. The heating medium enters the coil through a valve d and leaves the coil through a valve d^2 and suitable pipe connections. Any other means for heating the material to be mixed may be 15 employed.

E represents a safety valve mounted on the tank to prevent the gas in the tank from attaining an excessive pressure, and E' represents a pressure gage whereby the pressure 20 within the tank can be determined.

The two paddles B B' serve not only to give the liquid a whirling motion, but also to thoroughly mix or agitate the same so that all parts of the liquid will be exposed to the 25 action of the gas.

The apparatus is particularly desirable for use in hydrogenizing fats and oils, since by operating the paddles at a fairly high rate of speed, the liquid will be projected 30 violently against the top of the tank by the blades C and will be broken up into a spray or mist. Fats and oils treated in this manner absorb hydrogen much more rapidly than by discharging a stream of oil or fat 35 from a nozzle through the gas. In the use of the apparatus for hydrogenizing fats, oils or the like, the liquid to be hydrogenized is admitted to the tank through either of the pipes a^2 a^3 until the tank is approximately 40 half full of liquid. The valves in the pipes a^2 a^3 are then closed and hydrogen may be admitted to the tank until the desired pressure is obtained. If desired, air may be removed from the tank so that very 45 little air remains in the tank with the hydrogen. After the liquid has been heated to the desired temperature, the operation of the paddles is commenced. Hydrogen may be admitted to the tank as required. The pipe 50 a^2 is preferably employed for drawing off

the hydrogenized liquid and a small quantity of liquid is left in the bottom of the tank, so that most of the catalyst remains in the tank. Other means for removing the air from the tank before admitting the hydrogen may be employed.

I claim as my invention:

1. An apparatus for hydrogenizing fats and oils, comprising a tank adapted to contain the fats and oils and hydrogen, a plurality of radially extending paddles adapted to be rotated for imparting a whirling motion to said fats and oils while in liquid condition, said paddles being inclined upwardly and rearwardly with regard to the direction 60 of movement thereof, stationary deflectors arranged on the walls of said tank and extending into the fats and oils, said deflectors being inclined upwardly and forwardly with regard to the direction of movement of the liquid for causing portions of the liquid 65 fats and oils to be projected upwardly against the cover and to descend through the gas in said tank in finely divided form, and means for admitting hydrogen to the tank during 70 the operation of the apparatus.

2. An apparatus for hydrogenizing fats or oils, comprising a closed tank adapted to contain said fats or oils, means for admitting hydrogen to said tank, means for applying heat to the fats or oils in the tank, a rotary shaft extending into said tank, paddles connected to said shaft and arranged near the upper and lower surfaces of the body of the fats or oils to impart a rotary motion to 80 the fats or oils, and stationary deflectors arranged on the walls of the tank and extending into the body of said fats or oils, said deflectors being inclined upwardly and forwardly with regard to the direction of movement of the fats or oils for causing portions thereof to flow upwardly on said deflectors and to be projected upwardly against the 85 cover and to descend through the hydrogen.

Witness my hand, this 7th day of July, 95 1914.

FREDRICK N. ARNOLD.
